United States Patent Office

Des. 186,143
Patented Sept. 15, 1959

186,143

TAPE DISPENSER

Jean O. Reinecke, Chicago, Ill., assignor to Derby Sealers, Incorporated, Ansonia, Conn., a corporation of Connecticut

Application April 13, 1959, Serial No. 55,484

Term of patent 14 years

(Cl. D74—1)

Fig. 1 is a side elevational view of a tape dispenser embodying my new design;

Fig. 2 is a top plan view thereof; and

Fig. 3 is a front elevational view.

I claim:

The ornamental design for a tape dispenser, substantially as shown.
